(57) **CLAIM**

The ornamental design for a bleed ring body, as shown and described.

DESCRIPTION

FIG. 1 is a three-quarter front perspective view of the bleed ring body.

FIG. 2 is a front view of the bleed ring body.

FIG. 3 is a back view of the bleed ring body.

FIG. 4 is a side view of one side of the bleed ring body.

FIG. 5 is a side view of the opposite side of the bleed ring body.

FIG. 6 is a top view of the bleed ring body; and,
FIG. 7 is a bottom view of the bleed ring body.

The broken line showing of the assembly is included for the purpose of illustrating environmental structure and forms no part of the claimed design.

1 Claim, 5 Drawing Sheets
